UNITED STATES PATENT OFFICE.

THERON W. DE MOTT, OF OXFORD, WISCONSIN.

VENDING-MACHINE.

1,268,331.

Specification of Letters Patent. Patented June 4, 1918.

Application filed August 25, 1917. Serial No. 188,213.

To all whom it may concern:

Be it known that I, THERON W. DE MOTT, a citizen of the United States, residing at Oxford, in the county of Marquette and 5 State of Wisconsin, have invented certain new and useful Improvements in Vending-Machines, of which the following is a specification.

This invention relates to a coin controlled 10 vending machine, and is particularly designed for the delivery of package articles. The primary object of the apparatus is to provide a machine so constructed as to prevent defrauding the same by the insertion 15 through the coin slot of tokens, washers, coins of less than proper value and other articles, such articles being ejected from the coin slot before reaching the operating devices, or if through some mischance an article should pass to the operating devices, 20 means are there provided to lock said devices and prevent movement thereof, and thus withhold the issuance of a package.

Another object of the invention is to provide manually operable means for ejecting 25 the packaged article, the operation of said means being controlled by the coin-operated means which locks the package operating means against movement until the movement of the coin operating means has been completed, whereupon the former means 30 may be operated to eject a single package and then be locked against other movement until the insertion in the machine of another 35 coin of proper value.

A further object of the invention is to provide means for preventing the insertion within the machine of a wire or other article 40 to engage a package and cause the same to be withdrawn from the machine, all openings through the casing of the machine by which an object of any sort may be inserted being 45 protected by covers, guards or shields so as to render it impossible to reach packages for the purpose of removing the same.

With the above as the principal objects in view and other objects to be set forth in detail hereinafter, the invention consists in the novel construction, combination, and arrangements of parts hereinafter described, 50 pointed out in the appended claims and illus-

trated in the accompanying drawings, in which—

Figure 1 is a perspective view of the complete vending machine in position for use, 55

Fig. 2 is a rear elevation of the interior operating mechanism, the casing being shown in section,

Fig. 3 is a vertical sectional view from front to rear on the line 3—3 of Fig. 2 looking in the direction of the arrows, 60

Fig. 4 is a similar view on the line 4—4 of the same figure,

Fig. 5 is a horizontal sectional view of the machine on the line 5—5 of Fig. 2 looking 65 upwardly,

Fig. 6 is a similar view on the line 6—6 of the same figure looking downwardly,

Fig. 7 is an enlarged detail view in elevation of the coin operated mechanism, 70

Fig. 8 is a longitudinal sectional view on the line 8—8 of Fig. 7,

Fig. 9 is a vertical cross sectional view on the line 9—9 of the same figure,

Fig. 10 is a detail perspective view of a 75 part of the locking mechanism for holding the package delivery slide against improper operation.

Fig. 11 is a vertical transverse sectional view through the base of the machine showing 80 the article delivery slide, the locking means therefor, and the article delivery fingers carried thereby.

Figs. 12 and 14 are sectional views similar to Fig. 8 illustrating the operation of the 85 lock for checking movement of the coin delivery slide when a coin or token of improper size is inserted in the machine.

Fig. 13 is a detailed side view of the two part coin delivery slide with an undersized 90 coin or token between said parts and the lock engaging said coin, and

Fig. 15 is a sectional view through the coin chute on the line 15—15 of Fig. 4.

In the drawing 20 indicates the base of the 95 machine which may be of wood or metal and to which is secured vertical posts 21 extending upwardly from the top of the base to support a horizontal platform 22 spaced a short distance from the base as shown in 100 Figs. 2, 3 and 4. Covering the base and the platform 22 is a casing 23 comprising a back

plate 24 made preferably of sheet steel and firmly secured to the bottom 20, the side and top edges of said back plate being turned inwardly to form flanges 25, over which the front 26 is adapted to fit snugly. The front of the casing 26 is made of sheet steel of a somewhat box-like form comprising a front proper 27, sides 28, and top 29, the sides and top when in position engaging at their rear edges over the flanges 25 with the bottom of said sides and front 27 surrounding the edges of the base 20 and platform 22. Fingers 30 riveted to the inner side of the front 27 at the bottom edge thereof engage openings in the base 20 to prevent forcible separation between the base and the casing. A vertical partition 31 is secured to the platform 22 and extends to the top of the casing and from the front to the rear thereof, dividing said casing into two substantially equal chambers 32 and 33. Fixed to the partition 31 at the top thereof and adjacent the front is a lock 34, by means of which the casing is secured at its upper end against removal and which will permit authorized persons to open the machine when necessary to renew the packages and remove the coins.

Screwed or otherwise fastened to the side of the partition 31 within the chamber 32 is a horizontal guide-way 35 that extends from the front substantially to the rear of the partition and within which is mounted the two members 36 and 37 of the coin slide. These two members are in horizontal alinement and their adjacent ends contact when the slide is moved to operate the machine.

The contacting ends of the slides 36 and 37 are each provided with semi-circular concave depression 38 which, together form an opening of the exact size of the coin by which the machine is operated. Projecting laterally from the front end of slide member 36 is a pin 39, said pin extending through a slot 40 in the guide 35. By means of this pin the slide member 36 is manually operated and through the intervention of the coin the slide member 36 is caused to move along the guide 35 and deliver the coin into a chute 41 to be conveyed to a suitable receptacle.

At the side of the guide 35 is a horizontal push rod 42 mounted in brackets 43 projecting from said guide 35. This push rod passes through the front of the casing and 55 is fitted with a button or other finger piece 44 on the end which on being pressed inwardly by the finger moves the rod transversely of the machine, said rod being returned to normal position by means of 60 springs 45 and 46 hereinafter referred to. Depending from the under side of the push rod 42 is a lug 47 having a perforation therethrough for the pin 39 so that as the push rod is moved longitudinally, the slide member 65 36 is also moved to operate the machine.

after a coin of proper value has been deposited. A pin 48 projects from the rear member 37 through a slot 49 in the guide 35 to which pin is attached one end of the spring 46, the opposite end being fastened at 50 to the guide 35, said spring tending to maintain the slide member 37 in its forward position and return said slide when pushed rearwardly through the operation of the machine, the pin 48 abutting against the forward edge of the slide 49 limits the forward movement of the slide member 37. 70 75

Fastened to the side of the partition 31 above the guide 35 is a coin chute 51, said chute extending downwardly first at an angle and then in a curved direction to the top of the guide 35 through which is formed an opening for the passage of the coin. The coin chute is in the form of a flat tube, the opening therein being of the exact dimensions of the diameter and thickness of the coin of the proper value for operating the machine, the lower end of the coin chute opening through the guide 35 immediately above the forward end of the coin slide member 37 so that when a coin is placed in the chute it drops into the guide 35 and comes to rest in front of the depression 38 in the slide member 37 and in rear of the slide member 36. Through the front of the casing 26 opposite the entrance to the coin chute 51 is formed an opening that is preferably covered by a plate 52 having a coin opening therethrough of the exact dimensions of the coin so that coins, tokens and other articles of greater diameter or thickness cannot be introduced into the coin chute. Articles of the same or less diameter and of less thickness when inserted in the coin chute will fall through a slot 53 at the bottom of the chute, or if of iron or steel such as washers, these will be deflected and withdrawn from the chute by a magnet 54 secured to the partition adjacent the coin chute. The delivery chute 41 extends downwardly and rearwardly through the partition 31 in rear of the outlet end of the coin chute 51, and when the coin slide is moved rearwardly with a coin of proper value therein, this coin will be delivered, as more fully described here- 115

be delivered, as more fully set forth in the application for a patent filed by me on January 10, 1928, Serial No. 480,330, the disclosure of which is incorporated herein by reference. In accordance with the present invention, however, the coin delivery chute 41 is provided with a coin slide movement, so that when a coin is delivered into the chute 41, it will be caused to move along the slide movement, and when the coin reaches the end of the slide movement, it will be delivered into the coin delivery chute 41. The coin slide movement is provided with a locking pawl 55 which is seated in a horizontal slot 56 in the partition 31. The front end of the pawl 55 is held in contact with the slide member 37 when the machine is in an inoperative position by the spring 57 attached to an arm 58 on the pawl and to a pin or eye 59 projecting from the partition 31. Upon operation of the coin slide with a coin of proper value therein, the latter and the slide 120

members 36 and 37 being of equal thickness, will pass freely under the pawl 55 to the limit of movement, but should the coin be of smaller diameter than the space formed by 5 the depressions 38 in the slide members, the pawl 55 under tension of the spring 57 will enter the space between the slide member 37 and the coin as shown in Figs. 12 and 13 and engaging said coin will lock the slide and 10 prevent further rearward movement thereof. Should the coin be of proper diameter but thinner than the slide members, the pawl will not engage the coin which passes freely, but will engage the edge of the depression 15 38 in slide member 36 which being thicker than the coin projects beyond it, and stops further movement of said slide before it has completed the operation of unlocking the package delivery mechanism.

20 To prevent the return of the coin delivery slide after the coin has passed the detector pawl 55 and before it has reached the said chute 51, means are provided which consist of a pawl 50^a pivotally mounted on the partition 31, from the free end of which pawl a lug 51^a projects to bear upon the push rod 42. In the present instance, this pawl is 25 shown above the push rod, its finger 51^a being held in contact with the push rod by gravity. At a suitable point in the top of 30 the push rod 42 is a notch 52^a with which the lug 51^a is adapted to engage and prevent return of the push rod after the latter has been moved inwardly sufficiently far to carry 35 the coin beyond the detector pawl 55. Affixed to the side of the push rod 42 inwardly from the notch 52^a is a post 53^a that rises above the push rod and has secured on its upper end a spring finger 54^a which curves 40 downwardly and bears upon the push rod just forwardly of the notch 52^a and serves, upon return of the coin delivery slide, to engage the lug 51^a and lift the pawl 50^a over the notch and so permit return of the coin 45 slide to normal position.

The package ejecting mechanism is carried upon a rectangular frame 60 supported on the under side of the platform 22 in brackets 61 and loops 62. The frame may 50 be made in any desirable manner and of any material but in the present instance, is shown as formed of two longitudinal bars 63 and 64 connected together at their ends by transverse rods 65 and 66, said rods preferably, 55 being circular in cross section. The bar 63 is shown supported on the brackets 61 while the rods 65 are slidably mounted in the loops 62 near the side of bar 64. The frame 60 is adapted to be moved in its support 60 from one side of the machine to the other by means of a stem 67 attached to the frame and projecting horizontally through a slot 68 in the front of the casing 26. Each complete movement of the frame to the right or to 65 the left results in the ejection of a package

from the machine in a manner to be described later.

On the under side or face of the bar 64 of the frame 60 are formed two groups of ratchet teeth 69 and 70, the groups of teeth 70 extending from the respective cross rods 65 and 66 inwardly toward each other for a distance equal to or slightly greater than the length of movement of the frame 60. Pawls 71 and 72 are forced by springs 73 normally 75 into engagement with said teeth, which, by the way, face in opposite directions, that is to say, one set of teeth sliding freely over the pawl when the frame is moved in one direction, while the other set of teeth is adapted 80 to engage its pawl and prevent movement, unless the pawl is by some means held away from the teeth. This is to prevent reverse movement of the frame 60 before it has made a complete movement. The pawls 71 and 72 85 are pivotally mounted on brackets 74 and 75 fastened to the under side of the platform 22 and are in facing relation as shown. Below the series of ratchet teeth 69 and 70 are arranged two flat springs 76 and 77, the 90 former extending longitudinally of the row of teeth 69, while the latter spring 77 is similarly disposed below the teeth 70. These springs are spaced at their inner ends, or ends nearest the center of the bar 64, a short 95 distance below the inner ends of the respective series of teeth and both springs are connected to the bar at these inner ends by brackets 78. The opposite or outer ends of the springs curve upwardly toward the bar 100 64 and bear with spring pressure thereon, the length of these springs being such that when the frame 60 is moved its full distance of movement to either side of the machine, the spring on the opposite side of the frame 105 will have passed inwardly beyond the operating end of the pawl of the same side so that upon reverse movement of the frame 60, the end of said spring in contact with the bar 64 will engage and depress the pawl and 110 hold it away from the teeth on the bar 64. This is necessary as the teeth face toward the pawl and would engage therewith and prevent movement of the frame, unless the pawl is held away from the teeth. Upon completion 115 of movement of the frame 60, the pawl, thus lifted, will pass over the opposite end of the spring and be forced by its own spring into contact with the ratchet teeth again. The upper side of the bar 64 of the frame 60 120 is provided with four notches so disposed that when the frame 60 is at the extreme of movement in one direction, two of said notches 79 and 80 will be in line with the opposite sides of the partition 31, while the remaining two notches 81 and 82 will be brought to the same positions when the frame 60 is pushed to its limit of movement 125 at the opposite side of the machine. The object of these notches is to lock the package 130

delivery slide from movement until released by the proper and complete movement of the coin delivering mechanism, the operation of which will now be described.

5 An upright lever 83 is pivoted intermediate its ends to the side of the vertical partition 31 below the guide 35 and on the same side of the partition as the push rod 42, the upper end of said arm being broadened and 10 held in contact, by the spring 45, with the inner end of the push rod 42. The lower end of the lever 83 is connected by a link 84 with one arm of a bell-crank lever 85 pivoted at 86 to the partition 31. The other 15 arm of the bell-crank lever 85 is pivotally connected to a vertically movable dog 87 slidable through an opening in the platform 22, its lower end entering for a suitable distance, one or the other of the notches 79 and 81. When the vending machine is at rest, 20 the dog 87 is in elevated position and withdrawn from locking engagement with either coöperating notch in the frame 60 but when the push rod 42 is forced inwardly, its inner 25 end rocks the lever 83 and through the connections described, the dog will be forced downwardly and engages one or the other of notches 79 or 81. On the opposite side of the partition 31, is a second dog 88 parallel 30 to the dog 87 and also movable vertically through an opening in the platform 22. The upper end of the dog 88 is connected by a vertical link 89 to a horizontal lever 90, pivotally mounted intermediate its ends to the 35 partition 31. A second link 91 connects the opposite end of the link 90 with a horizontal arm 92 fixed on a shaft 93 passing through the vertical partition 31 to the opposite side, where it is provided with a depending arm 94, the lower end of which is broadened and 40 lies in the line of movement of the push rod 42 and is operable by said rod to rock the shaft 93. A spring 95 is connected to the arm 92 and acting through the links and levers described, tends to hold the dog 88 in 45 locking engagement with one or the other of the notches 80 or 82 in the frame 60.

The mechanism described for maintaining the package slide immovable and preventing 50 the same from being actuated to cause packages to issue from the casing, is locked under normal conditions so that said package slide cannot be moved except when a coin of proper value has been placed in the 55 chute 51. This locking means comprises the dogs 87 and 88, one or the other of which is in engagement with the notches 79-80 or 81-82. Normally, or when the machine is at rest, the dog 88 is forced to its 60 lowermost position by the spring 95, so that its lower end will interlock with the notch 80 or 82, while the dog 87 will be in elevated position. When, however, the coin of proper value has been placed in the coin chute, and 65 the push rod 42 moved inwardly, the first

operation will be to swing the lever 83 on its pivot and through the connections 84, 85, depress the dog 87 into the notch 79 or 81. The rod 42 at the end of its movement engages the lever 94 and swinging it toward 70 the back of the casing will through the shaft 93, rock the series of levers 92 and 90 and raise the dog 88 from the notch in the package slide. When the dog has been drawn out of engagement with the notch, a bolt 96, 75 (see Fig. 10), mounted on the platform 22 is forced by a spring 96^a into engagement with a notch 88^a in the dog 88 to hold the same in elevated position until the package has been delivered. The bolt 96 is pivoted on 80 one end of a rocking lever 97 fulcrumed at its other end at 98 to the platform. From this lever links extend in opposite directions, one of which links 99 is connected loosely to one end of a lever 100, that is centrally pivoted to the platform, its opposite end extending a short distance beyond its pivot and being engaged by the hooked end of a short wire 101 that extends back toward the lever 97 and engages a trigger 102 adapted 85 to be operated by the transverse rods 65, 66 of the package slide when moved to that side of the machine. The rod 101 is not connected to the lever 100, but merely bears against it so that when the trigger is moved 90 in the opposite direction by the reverse movement of the package slide, it will not rock the lever 100, and so disturb the bolt 96, but will press upon a spring 103 which will return the parts to position when the 95 package slide has moved out of range thereof. On the other side of the lever 97 is a link 104 that through several connections shown, is engaged with a lever 105 similar to the lever 100, and similarly operated so that 100 whenever the package slide is moved to one end or the other of the casing, this system of levers will be operated and the bolt 96 withdrawn from engagement with the 105 dog 88. 110

In the operation of this machine, when a coin is placed in the coin chute 51, it passes down said chute if of proper value and enters the space 38 between the slides 36 and 37. If the coin is too small in any way or 115 made of iron, it will either drop out of the bottom of the coin chute through slot 53 or be attracted by the magnet 54, or if it passes said slot and the magnet, enters between the slides 36 and 37, the machine will fail 120 to completely operate, while if said coin is moved along the guide 35 by the rod 42 for a short distance, the dog 55 at the mouth of the coin discharge 41 will engage the coin or the slide and prevent further movement thereof, so that it being impossible to push the rod 42 its full distance, the package slide will remain locked. If the coin 125 be of proper value and size, the two slides will move easily in an endwise direction, the 130

rod 42 first swinging the lever 83, which lies against its end and holding it inclined, pushes the dog 87 into one of the notches in the top of the package slide and holds it thus engaged. Further movement of the rod 5 will bring its end into engagement with the lever 94 and cause it and its shaft 93 to swing in a direction that will raise the dog 88 from its notch in the package slide until 10 the bolt 96 engages the notch 88^a in said dog and so holds it away from the package slide. At this time, the rod 42 has been forced inward as far as it will go, permitting the coin to be forced from between the slides and 15 through the coin delivery 41 by a spring 106 secured in any suitable manner to the vertical partition 31. Upon releasing the rod 42, the springs 45 and 46 acting indirectly thereon will return the rod to normal position. The lever 83 during the movement of 20 the rod 42 has been held by said rod in position to force the dog 87 into one of the notches 79 or 81 in the package slide to prevent movement thereof during the disengagement of the dog 88, but as soon as the 25 rod returns to normal position, the lever 83 is released and through the spring 45 is drawn to vertical position, the connections of said lever raising the dog 87 from engagement with the notch in the package 30 slide. Both dogs 87, 88 being now elevated, the package slide is released and may be moved to one side or the other of the casing by grasping the handle 67 and giving it a 35 slight push in the direction required. Each movement of the package slide 60 will withdraw a package of the article to be dispensed from alternate sides of the casing, these packages being stored in vertical boxes 107 40 that extend from the top of the casing to the bottom, there being an opening on the facing sides of said boxes for the packages to pass through.

The package slide 60 has two upright fingers 108 in line with the inner sides of the boxes 107 and two spring hinged fingers 109 immediately below the outer sides of the box. Between these fingers, the packages fall when the slide passes under the box and 45 when the slide is away from the box the package will rest upon the top of the platform 22, the spring finger turning down to pass under the package and get behind the same as the slide 60 is moved toward that end or 50 side of the machine. The movement of the package slide grips the said package between the fingers 108 and 109 of the respective sides and carrying the same toward the center of the machine finally permits it to 55 drop therebetween onto an inclined trough 110 down which it slides to the front of the machine below the handle 67, within easy reach of the purchaser. The movement of the package carrier to deliver the purchased 60 package requires the movement of said car-

rier to the opposite end of the machine. This movement will bring one or the other of the transverse rods 65, 66 at the end of the carrier into engagement with one or the other of the triggers 102 and rocking said trigger, will pull the rod 101 and through connection with the lever 97 cause the latter to move in a direction that will withdraw the bolt 96 from the notch in the dog 88, permitting the latter to drop and when the notch 80 or 82 is in line with said dog, the latter enters and prevents further movement of the package delivery slide until another coin has been deposited.

What is claimed is:

1. In a vending machine, the combination of an article delivery slide, a coin receiving chute, coöperating slides between which the coin is delivered from the chute and by which it is carried to the discharge duct, means for manually operating said slides in one direction, resilient means for independently returning each slide to normal position, and means for locking said article delivery slide in the normal position of the machine and during the movement of the coin slides.

2. In a vending machine, the combination of an article delivery slide, a coin receiving chute, coöperating slides between which the coin is delivered from the chute and by which it is carried to the discharge duct, means for manually operating said slides in one direction, means for locking said slides to prevent complete movement with a coin of improper size, resilient means for independently returning each slide to normal position, and means for locking said article delivery slide in the normal position of the machine and during the movement of the coin slides.

3. In a vending machine, the combination of an article delivery slide, a coin receiving chute, coöperating slides between which the coin is delivered from the chute and by which it is carried to the discharge duct, means for manually operating said slides in one direction, means for locking said slides to prevent complete movement thereof when the coin is of other than the proper value, means normally locking the article delivery slide, means actuated by the coin delivery slide for releasing said locking means, and a second locking means moved into engagement with the article delivery slide by the movement of the coin delivery slides and released to permit movement of the article delivery slide only upon the completion of the return movement of the coin delivery slide.

4. In a vending machine, the combination of a coin receiving chute, manually operable coöperating slides of equal thickness to a proper coin and abutting endwise between which ends the coin is delivered from the coin chute and by which it is carried to the

discharge duct, and means movable into the line of movement of said coin delivering slides to engage the same or the coin and stop movement thereof and prevent operation of the machine when other than a proper coin is placed between the coöperating slides.

5. In a vending machine, the combination of a manually operable article delivery slide, 10 a coin receiving chute, coöperating slides between which the coin is delivered from the chute and by which it is carried to the discharge duct, means for manually operating said slides in one direction, independent resilient means for returning each of 15 said slides to normal position, means for locking the article delivery slide while the machine is inoperative, means actuated by the coin delivery slide for unlocking said 20 means, means for holding the same unlocked, a second locking means normally released from the article delivery slide moved to lock the same by the coin delivery slides and hold the same locked until the complete 25 return movement of said slides, and means actuated by the article delivery slide for returning the first named locking means to normal locked position after delivery of the article.

30 6. In a vending machine, the combination with a coin delivery slide comprising two aligned independent members of the same thickness as a proper coin having depressions in their adjacent ends which together 35 form an opening of the exact size to receive the coin, manual operating means connected to one of said slide members for moving both slides in one direction, a spring connected to each of said members for re- 40 turning them to normal position, a coin receiving chute for directing the coin between said slides, a coin discharge duct, and means adapted to engage one of said slide members or the coin for preventing the complete 45 movement of said slides when a coin of other than proper thickness and diameter has been received between the members thereof.

7. In a vending machine, the combination 50 of a manually operable package delivery slide, a two-part coin slide, said parts being disposed in endwise relation and each having a depression in one end which depressions together form an opening of the 55 exact size of the coin by which the machine is operated, manually actuated means for moving said slide members, a spring member connected to each of slide members for returning them to normal position, a locking 60 dog adapted to engage said slide and prevent complete movement thereof when a coin of other than proper value has been placed within the opening between the slide members, and locking means to prevent the 65 movement of the package delivery slide for

the issuance of a package until the complete movement of the coin delivery slide has been performed.

8. In a vending machine, the combination with an article delivery slide, a coin delivery slide comprising coöperating members between which a coin of proper value is deposited, a coin discharge duct, a push rod for operating the coin delivery slide to convey the coin to the discharge duct, locking 70 means engaging said article delivery slide to prevent operation thereof in the normal position of the machine, a second locking means normally disengaged from said slide but adapted to be moved into engagement therewith, means actuated by the push rod at the beginning of its forward operation for moving said second locking means into engagement with the package delivery slide and at the completion of said movement to unlock the first named means and finally at the end of the return movement of said push rod to wholly unlock the package delivery slide and permit operation thereof.

9. In a vending machine, the combination of a manually operable article delivery slide, a coin slide comprising two aligned members having depressions in their adjacent ends which together forms an opening of the exact size of the coin which operates the machine, manually operable means connected to one of said slide members for moving both slides in one direction, a spring connected to each of said members for returning them to normal position, and locking 95 means to prevent movement of the article delivery slide actuated by means connected to the coin delivery slide during the complete movement thereof.

10. In a vending machine, the combination of a manually operable article delivery slide, a coin delivery slide comprising two aligned coöperating endwise abutting members having depressions in their adjacent ends which together form an opening of the exact size of the operating coin, manually operable means connected to one of said members for moving both of them in one direction, a spring connected to each of said members for returning them to normal position, a locking means for engaging said article delivery slide to prevent movement thereof when the machine is in normal position, a second locking means actuated by means connected to the coin delivery slide 100 for engaging said article delivery slide during movement of the coin delivery slide, means actuated through movement of the coin delivery slide for unlocking the first of said locking means, means for holding 110 said locking means in its unlocked position, and trip means actuated by the movement of the article delivery slide for releasing said trip means.

11. In a vending machine, the combina- 115

- tion of a manually operable article delivery slide, a coin delivery slide comprising two alined coöperating endwise abutting members between which the operating coin passes, manually operating means connected to one of said members for operating both, a spring connected to each of said members for returning them to their normal positions, a locking means for preventing movement of said article delivery slide in the normal position of the machine, a second locking means for engaging said article delivery slide at the beginning of movement of the coin delivery slide, means actuated through movement of the coin delivery slide at the end of its forward movement for unlocking the first of said locking means, means for holding said locking means in its unlocked position, means actuated by the coin delivery slide at the completion of its return movement for unlocking the second locking means, and a trip device actuated by the article delivery slide at the completion of its movement in each direction to release the holding means of the first named locking device and permit said locking device to engage the article delivery slide and hold it immovable until the deposit of another coin into the machine.
12. In a vending machine, a coin slide therefor comprising two endwise alined coöperating members normally separated but adapted to abut and of a thickness equal to the operating coin, each of said members having a depression in its abutting end that together form an opening to receive a coin of the exact diameter of the coin for operating the machine, means attached to one of said slides for moving both of them in one direction to deliver the coin to the machine, and an independent resilient means acting on each slide member to return said members to normal position.
13. In a vending machine, a coin delivery slide therefor comprising two endwise alined coöperating members normally separated but adapted to abut and of a thickness equal to the operating coin, each member having a depression in its abutting end that together form an opening to receive a coin of the exact diameter of the coin for operating the machine, manually operable means connected to one of said slide members for moving the slide in one direction to deliver the coin to the machine, independent resilient means acting on each of said slide members to return them to normal position, and a locking device acting on the slide member provided with the manually operable means to prevent return of the coin delivery slide after operation of same has begun until the coin has been delivered to the machine.
14. In a vending machine, a coin delivery slide therefor comprising two endwise alined coöperating members adapted to abut and
- having a thickness equal to the coin for operating the machine, each of said members being formed with a semi-circular depression in its abutting end which together form an opening of a size equal to the diameter of said coin, a manually operable push rod connected to one of said slide members for moving said slide in one direction to deliver the coin to the machine, said push rod having a notch in one side, a spring operable on each of said slide members for returning the said members to normal position, a pawl pivoted to the frame of the machine and adapted to bear on said push rod for engaging the notch therein and preventing return of the slide until the coin has been delivered to the machine, and a resilient bridge connected to said push rod, extending over the notch to lift said pawl and prevent engagement thereof with the notch upon return of the slide after the latter has been moved to its extreme inward position.
15. In a vending machine, the combination of a coin delivery slide, a package delivery slide adapted to deliver a package from the machine at each transverse movement of said slide, locking means normally in engagement with said package delivery slide to hold the same immovable, a second locking means normally out of engagement with the package delivery slide, means operated by the coin delivery slide for withdrawing the primary locking means from the package delivery slide, means operated by the coin delivery slide for moving the secondary locking means into engagement with the package delivery slide at the beginning of movement of the coin delivery slide and holding the package delivery slide locked until the complete return of the coin delivery slide, means for holding the primary locking means in its disengaged position, and means controlled by each transverse movement of the package delivery slide upon the completion of its movement for tripping said holding means and releasing the primary locking means to engage the package delivery slide.
16. In a vending machine, the combination of a coin delivery slide, a package delivery slide adapted to deliver a package from the machine at each transverse movement of said slide, a sliding bolt normally in engagement with a notch in the package delivery slide for locking said slide against movement, a second sliding bolt also adapted to engage a notch in the package delivery slide and normally out of engagement therewith, means operated by the coin delivery slide at the completion of its movement in one direction for withdrawing the primary locking bolt from engagement with the package delivery slide, other means also operated by the coin delivery slide at the beginning of its movement for moving the secondary locking

bolt into engagement with the package delivery slide and holding said slide locked upon the complete return of the coin delivery slide, means for holding the primary locking bolt in its disengaged position, means controlled by each transverse movement of the package delivery slide upon the completion of its movement for tripping said holding means and releasing the primary locking means to engage the package delivery slide, a series of ratchet teeth on

each end of the package delivery slide reversely disposed, and a pawl adapted to engage with one or the other of said series of teeth during the delivery movement of the slide and prevent return thereof. 15

In testimony whereof I affix my signature in presence of two witnesses.

HERON W. DE MOTT.
